CELLULOUS RIBBON SPOOL AND THE
METHOD OF CONSTRUCTING THE SAME

Morris Katz, Bronx, N. Y.

Application May 18, 1939, Serial No. 274,314

7 Claims. (Cl. 206—59)

This invention relates to the manufacture of spools of cellulosic ribbon composed, for example, of "Cellophane" in various plain colors or combinations of colors as well as in many ornamental designs suitable for various seasons and occasions; and more particularly an object of the invention consists in the method of arranging and mounting such ribbons on spools so as to preserve the ribbons, maintaining the same in a soft, pliable state so as to facilitate a more convenient and practical use thereof; a further object of the invention being to provide a spacing or filler strip associated with the cellulosic ribbon on the spool and between the separate windings or turns of the ribbon on the spool to act as a carrying or supporting agent for a fluid or compound to maintain the ribbon in its soft and pliable state; a further object being to provide an embossed or characterized filler or spacer strip of the character described which will operate to emboss or characterize the "Cellophane" ribbon when wound on the spool to give other characteristics and structural features to the resulting ribbon; and with these and other objects in view, the invention consists in a device of the character described, constructed in accordance with the method more fully hereinafter described and claimed.

The invention is fully disclosed in the following specification, of which the accompanying drawing forms a part, in which the separate parts of my improvement are designated by suitable reference characters in each of the views, and in which:

Fig. 1 is a perspective view of a spool illustrating one adaptation of the invention.

Fig. 2 is a view similar to Fig. 1 showing another adaptation of the invention.

Fig. 3 is a partial section on the line 3—3 of Fig. 2 on an enlarged scale, exaggeratedly illustrating the embossing effects upon the resulting ribbon, and

Figs. 4, 5, 6 and 7 inclusive, are detail plan views showing different methods of applying the softening solution or agent to the spacing or filler strip.

In the construction of spools of cellulosic ribbon such as "Cellophane" ribbon, it has been commonly experienced that the ribbon, after laying around in store rooms, on the counter, etc., as well as laying around in the home prior to uses or intermittent uses thereof, that the ribbon has become stiff and hard which has materially affected the use thereof and in fact has rendered the use objectionable. This stiffness or hardness has also caused the ribbon to become brittle

and to rupture more readily, especially in the process of time.

It is one of the purposes of my invention to produce ribbon spools of the character under consideration wherein a filler or spacing strip is employed which is treated with a solution or agent which will operate to maintain the separate windings of the ribbon on the spool in a soft and pliable state for a long period of time. While it is conceivable that the outer winding of the ribbon may become somewhat hardened over a period of many months, the inner or covered windings of the ribbon upon the spool will be maintained in the desired soft, pliable state.

15 In Fig. 1 of the drawing, 10 represents the usual paper, cardboard, or other core of the spool upon which the filler or spacing strip 11 and cellulosic ("Cellophane") strip 12 are wound. The strip 11 is preferably wider than the ribbon 12 so as to 20 guard the edges of the ribbon in the handling of the spool and also to effect a better seal of the ribbon within the respective windings, it being understood that the strip 11 is of softer texture than the "Cellophane" strip 12, and in a tight winding, the "Cellophane" strip would not be 25 exposed or visible at the sides of the resulting spool.

The "Cellophane" strip 12 is shown as being plain in cross section for the purpose of simplifying the illustration, but in actual practice the side edges of the "Cellophane" strip or ribbon are folded inwardly to give strength thereto.

In the construction shown in Fig. 1, the entire strip 11 is saturated, sprayed, or otherwise treated with a solution consisting of water and glycerine with a sufficient amount of glycerine in the solution to leave a deposit of the glycerine on the strip 11, maintaining said strip soft at all times. In winding the strips 11 and 12 one upon the other in forming the spool, it will be understood that the separate coils of the strip 11 will engage upper and lower surfaces of the windings of the strip 12, whereby the close contact of the strips will enable the glycerine to be transmitted to the 40 "Cellophane" strip, preserving it in the soft and pliable state which is desired. It will of course be understood that the degree of treatment of the strip 11 will be regulated so as to prevent excessive saturation of the strip 12, but this can be controlled in many ways in the preparation and treatment of the strip 11. This strip 11 may be composed of various kinds and grades of paper, and particularly paper having sufficient absorbing properties to absorb and hold the solution therein. In the construction shown in Fig. 1, the strip 45

11 has a plain or finished surface, and in using a strip of this type and kind, the ribbon 12 will be maintained in a smooth state or condition at all times.

It is another feature of my invention, however, to provide a spacing or filler strip 11a, as is shown in Fig. 2 of the drawing, which is of a crinkled, embossed or otherwise characterized structure, the crinkling, embossing or the like being illustrated diagrammatically at 13. With an arrangement of this type, it will be understood that the resulting ribbon 12a will have thereon, when removed from the spool, embossings as at 14, thus breaking down the flatness or evenness of the ribbon and giving added characteristics thereto.

It will be readily understood that by reason of the contour of the strip 11a and the fact that the strips 11a, 12a are wound tightly one upon the other on the core 10a of the spool, the irregularities will be transmitted to or formed in the strip 12a. While in the illustration in Figs. 2 and 3 of the drawing, markings from one layer or turn of the strip 11a are shown, it will be understood that markings of another layer or winding of this strip will also act upon the strip 12a, as each turn or winding of the strip 12a is disposed between two turns of the strip 11a. Another method of carrying out the same effect as the strip 11a, is indicated in Fig. 7 of the drawing wherein the strip 11b is provided with a series of apertures or perforations 15. While different forms of perforations are shown, it will of course be understood that these perforations may be all of the same outline and may be made smaller and larger to provide predetermined effects.

In Figs. 4, 5 and 6 of the drawing, I have shown other methods of treating strips of the type and kind illustrated at 11, 11a, 11b in the application of the solution or softening agent thereto. In Fig. 4 of the drawing, 16 represents any suitable strip of this type and kind which has a series of transversely arranged and longitudinally spaced deposits of the solution as at 17, leaving therebetween, untreated sections 18. In Fig. 5 of the drawing a strip 16a is shown having two longitudinal ribbon-like deposits of the solution 17a arranged adjacent the side edge portions of the strip, leaving untreated longitudinal sections 18a. In Fig. 6 of the drawing, a strip 16b is shown having a combination of transverse deposits 19 and longitudinal deposits 20. It will of course be understood that any desired arrangement, contour or design of the deposits may be provided by simply constructing the applying means to suit the effect which is contemplated.

As another feature of the present invention, it should be noted that in addition to the saturant for maintaining the cellulosic material soft and pliable, the spacing means may have incorporated therewith, a suitable aromatic compound or compounds adapted to impart a desired scent or odor to the cellulosic material. Such an aromatic or volatile compound is preferably incorporated in the saturant, and it will be apparent that the entire area of the spacing means or strip may be treated with both the saturant and the aromatic compound. On the other hand, the desired effect may be produced by including the aromatic compound at intervals along the spacing means. By way of illustration in Figs. 4 and 6 of the drawing, the transverse treated portions 17 and 19 respectively may be alternately treated with the saturant alone and with the combined saturant and aromatic compound. It will be un-

derstood, however, that the precise amount and arrangement of the aromatic compound would depend entirely upon the particular effect desired in the cellulosic material.

5 While the improved spacing strip has been shown in the drawing as associated with a relatively narrow ribbon, it will be understood that a spacing strip made in accordance with the present invention may be employed with ribbons of 10 any width. It will be apparent in this connection that the spacing means is also applicable for use with sheets of cellulosic material, such for example, as sheets used in wrapping goods and small articles. A primary purpose for using the 15 spacing means in this connection, would be to impose some predetermined surface irregularity to the separate sheets while at the same time maintaining the cellulosic material soft and pliable. It will be apparent, however, that the use of a suitable aromatic compound in this connection is likewise of primary importance to produce 20 a scent or aroma on the cellulosic material. In this connection, it will be noted that the aromatic compound incorporated may produce a generally pleasing scent, or on the other hand may be 25 characteristic of the particular article which is to be wrapped.

As a still further feature of the present invention, it should be understood that when a 30 spacing strip treated with a saturant in the manner previously described, is wound intermediate successive windings of a cellulosic ribbon, there is a slight adhesion between the saturant of the strip and the ribbon which is diagrammatically shown in Figs. 1 and 2 of the drawing. This slight adhesion, while permitting the intentional unwinding of the ribbon, tends to materially decrease accidental unwinding and especially 35 the highly objectionable side-slip of the ribbon and spacing strip which is often experienced 40 and which often occurs in conventional ribbon spools.

Having fully described my invention, what I 45 claim as new and desire to secure by Letters Patent, is:

1. In a cellulosic ribbon spool of the character described, means for spacing the ribbon wound on said spool, said spacing means comprising an elongated strip of material wider than the ribbon and adapted to be arranged between successive windings of said ribbon, said strip completely enclosing the inner windings of said ribbon by extension of side edges of the strip beyond side edges of the ribbon, and said strip having absorbent properties and having incorporated therein a saturant adapted, by contact with the ribbon, to maintain said ribbon in a soft and pliable condition.

2. In a cellulosic ribbon spool of the character described, means for spacing the ribbon wound on said spool, said spacing means comprising an elongated strip of material wider than the ribbon and adapted to be arranged between successive windings of said ribbon, said strip completely enclosing the inner windings of said ribbon by extension of side edges of the strip beyond side edges of the ribbon, said strip having absorbent properties and having incorporated therein a saturant adapted, by contact with the ribbon, to maintain said ribbon in a soft and pliable condition, and said strip having an irregular surface contour adapted to impart corresponding irregularities to said ribbon.

3. In a cellulosic ribbon spool of the character described, means for spacing the ribbon wound

on said spool, said spacing means comprising an elongated strip of material wider than the ribbon and adapted to be arranged between successive windings of said ribbon, said strip completely enclosing the inner windings of said ribbon by extension of side edges of the strip beyond side edges of the ribbon, said strip having absorbent properties and having incorporated therein a saturant adapted, by contact with the ribbon, to maintain said ribbon in a soft and pliable condition, and said strip being crinkled to provide irregularities on said ribbon.

4. In a cellulosic ribbon spool of the character described, means for spacing the ribbon wound on said spool, said spacing means comprising an elongated strip of material adapted to be arranged between successive windings of said ribbon, said strip completely enclosing the inner windings of said ribbon, said strip having absorbent properties and having incorporated therein a saturant adapted, by contact with the ribbon, to maintain said ribbon in a soft and pliable condition, said strip having spaced apertures in predetermined pattern arrangement.

5. In a cellulosic ribbon spool of the character described, means for spacing the ribbon wound on said spool, said spacing means comprising an elongated strip of material adapted to be arranged between successive windings of said ribbon, said strip being wider than said ribbon, thereby adapting said strip to completely

enclose the inner windings of said ribbon, said strip comprising absorbent material and having associated therewith a saturant adapted to maintain the ribbon in a soft and pliable condition, said saturant being incorporated in predetermined portions only of said strip throughout the length thereof.

6. In a cellulosic ribbon spool having a plurality of successive turns of ribbon wound thereon, a spacing strip arranged continuously between successive turns of said ribbon, said strip being wider than said ribbon and of soft texture to completely enclose said ribbon, said strip being treated with a glycerine base saturant adapted to maintain the ribbon in a soft and pliable condition, and said saturant being arranged on predetermined spaced portions of said strip.

7. The herein described method of preserving and characterizing cellulosic ribbon on a spool, which consists in forming surface irregularities on a soft textured strip treated with a glycerine base saturant, arranging a ribbon in superimposed relation on said strip, and then winding said strip and ribbon on a spool, thereby enclosing inner layers of said ribbon between successive layers of said strip, permitting the saturant of said strip to maintain said ribbon soft and pliable, while at the same time imparting to said ribbon surface irregularities corresponding to the irregularities of said strip.

MORRIS KATZ.
